STOCKING

Julius Miran, Bronx, N. Y.

Application September 2, 1950, Serial No. 12,042

Term of patent 14 years

(Cl. D47—7)

To all whom it may concern:

Be it known that I, Julius Miran, a citizen of the United States of America, residing at 1721 Grand Avenue, Bronx, in the county of Bronx and State of New York, have invented a new, original, and ornamental Design for a Stocking, of which the following is a specification, reference being had to the accompanying drawing, forming part thereof.

In the drawing:

Fig. 1 is a side elevational view of my new stocking; and

Fig. 2 is a rear fragmentary elevational view.

The markings indicate a pair of parallel running stitches.

I claim:

The ornamental design for a stocking, substantially as shown and described.

JULIUS MIRAN.
